UNITED STATES PATENT OFFICE.

EMIL C. ANDERSON, OF DENVER, COLORADO.

LOCK-BOLT.

1,308,026.

Specification of Letters Patent.

Patented July 1, 1919.

Application filed February 18, 1918. Serial No. 217,972.

To all whom it may concern:

Be it known that I, EMIL C. ANDERSON, a citizen of the United States, residing in the city of Denver, county of Denver, and State of Colorado, have invented certain new and useful Improvements in Lock-Bolts, of which the following is a description.

My invention belongs to that general class of devices adapted to so engage a bolt and its coöperating screw-threaded nut that the two are substantially locked together and are not likely to become accidentally disengaged. It has for its object a very effective construction of a device of the class referred to which may be constructed at slight cost and may be used again and again without in any way affecting the efficiency of the locking feature.

To this end my invention consists in the novel construction, arrangement and combination of parts herein shown and described and more particularly pointed out in the claims.

In the drawings, wherein like reference characters indicate like or corresponding parts,

Figure 1 illustrates an end view of one form of my improved bolt with the coöperating parts in place in position thereon;

Fig. 2 is a perspective view of a detachable washer adapted to be placed upon the end of the bolt in the form shown;

Fig. 3 is a perspective view of the part coöperating with the washer shown in Fig. 2, by the operation of which the bolt is effectually locked to a nut placed thereon;

Fig. 4 is a longitudinal section through a part of a bolt of the form shown with the coöperating parts placed in position thereon and a nut mounted upon the bolt;

Fig. 5 is a similar section, showing the locking member retracted to lock the bolt within the nut;

Fig. 6 is an enlarged sectional view more clearly illustrating the locking action;

Fig. 7 is a central longitudinal section of the end of a bolt illustrating a modification, the parts being placed together in position for threading the nut shown thereon;

Fig. 8 is a diagrammatic view showing the end of the bolt with the guiding stem, the cam washer and the cam locking member for the preferred form illustrated in Fig. 7;

Fig. 9 is a top plan view of a bolt with

the guiding stem, having a nut locked thereon by my improved method and means;

Fig. 10 is a side elevation of a slightly modified form in which the cam face is formed integrally upon the end of the bolt;

Fig. 11 is a section showing a nut mounted in the form shown in Fig. 10;

Fig. 12 is a section showing an ordinary bolt without a guiding stem thereon formed to embody my invention; and

Fig. 13 is a section showing a modified form.

In the drawings, 1 illustrates the free end of a threaded bolt preferably having formed thereon an extended guiding stem 2. An upward extension 3 is in the form shown either rectangular or other form adapted for the reception of a suitable coöperating washer thereon and to prevent the rotation of the washer on the stem or the end of the bolt. 4 is a cam-faced washer adapted to be placed upon the stem 2 and provided with a central opening 5 conforming to the shape of the shoulder 3. The cam face is preferably provided with a shoulder 6, as illustrated. 7 is a coöperating part or follower of substantially the same diameter as the bolt and correspondingly threaded. It is provided on its lower face with a coöperating cam 8 with a coöperating shoulder 9. An opening 10 through the part is adapted to be loosely and rotatably mounted on the guiding and retaining stem 2, the washer 4 lifting said part above the square shoulder 3 to permit such rotation. The upper face of the part 7 is provided with any suitable or preferred construction 11 adapted for the engagement of a tool so that said part may be rotated. 12 is a nut of any preferred external form adapted to be screwed upon the end of the bolt.

As thus described, the cam washer 4 is placed upon the end of the bolt, the opening 5 thereof engaging the shoulder 3 so as to prevent the rotation of the washer upon the bolt. The part 7 is then loosely placed upon the cam with the shoulder 9 in contact with the shoulder 6 of the washer. While in this position the nut 12 may be readily threaded upon the bolt to the point desired, but should not be screwed down sufficiently far to disengage the threads of the part 7 from the nut. When the nut is properly set down, a tool may be applied to the part 11

and the part 7 forcibly retracted; the cam faces on the washer and said part serving to so force the part 7 longitudinally that the threads thereof are locked in frictional contact with the nut as clearly illustrated in Fig. 6.

When it is desired to remove the nut it will be necessary to again place the tool upon the part 11 and turn the same forward again, 10 bringing the shoulder 9 in contact with the shoulder 6 on the washer. This unlocks the bolt 2 from the nut, and the nut may then be backed off from the bolt, provided care is taken to prevent the part 7 rotating therewith. Any preferred means may be employed to prevent this. As shown in the drawings, I form a pinhole 13 through the washer and a corresponding pinhole 14 through the part 7, the two being so arranged 15 that when the shoulders 9 and 6 are in contact the holes 13 and 14 will register. A pin 15, clearly shown in Fig. 7, may then be loosely placed through both the parts, sufficiently locking them together and preventing the rotation of the said part 7. In this position the nut may as readily be removed from the bolt as though no locking means were employed. In the form shown in Figs. 7, 8 and 9, in place of the guiding 20 stem 2 having a shoulder 3 formed thereon, it is round or turned so that a washer placed thereon would readily rotate thereabout. In order to lock the washer which I have marked 16 upon the bolt, a pinhole 17 is 25 formed through the washer and a coöperating pinhole 19 formed in the face of the shoulder or end of the bolt, as indicated, and a pin 18 placed therein serves to lock the washer against rotation upon the bolt as before. The operation is otherwise substantially the same as described. I have indicated the hole in the washer for the reception 30 of the pin 15 by the numeral 20 and the corresponding hole through the part 7 by the numeral 21.

As shown in Figs. 10 and 11, instead of using a washer a cam-faced extension 22 is formed integrally upon the end of the bolt.

1. This, while operating in substantially 50 the same manner in locking the bolt to the nut, is a more expensive construction and the form illustrated in Figs. 7 and 8 is preferred because of economy.

In the form shown in Fig. 12, the end of 55 the bolt is not provided with a guiding or retaining stem, whose only function is to increase the convenience of assembling the parts. The means employed to prevent the rotation of the washer on the end of the bolt 60 and to temporarily engage the follower and washer while removing the nut, is substantially the same as shown in Figs. 7 and 8.

In Fig. 13 a reversal of the parts is shown in which the bolt 1 is recessed as at 23 for 65 the reception of a guiding stem 24 depend-

ing from the follower 25. Registering apertures are formed in the follower and end of the bolt for the reception of the locking pin as shown. The pin, however, is necessarily only used when the nut is to be removed to 70 conveniently prevent the cam follower backing and thus preventing the disconnection of the parts. The operation is substantially the same. Obviously the end of the bolt may be straight and a cam washer similar 75 to that shown in Fig. 2 employed, as in the other form.

It is obvious that the nut may be removed and reengaged any number of times without destroying the efficiency of the locking 80 means.

Having thus described my invention and its method of operation, I do not wish to be understood as limiting myself to the exact construction shown, there being various 85 modifications that could be employed, and that will readily occur to the skilled mechanic.

What I claim as new and desire to secure by Letters Patent is:—

1. A lock-bolt comprising a bolt reduced at the threaded end to form a projecting guiding stem, the annular face about the stem provided with a shouldered cam face, in combination with a coöperating part of a diameter corresponding to that of the bolt and similarly screw-threaded, provided with a coöperating and shouldered cam face and a coöperating part for the guiding stem, and means for engaging a tool with said 100 part to rotate the same.

2. A lock-bolt comprising a bolt reduced at the threaded end to form a projecting guiding stem and providing an annular face about the stem, a cam faced washer adapted to rest upon said shoulder, in combination with a coöperating part of a diameter corresponding with the bolt and similarly screw-threaded, said part provided with a cam face coöperating with that of the washer and an opening for the guiding stem, and means for engaging a tool with said part to rotate the same.

3. A lock-bolt comprising a bolt, a cam-faced washer adapted to rest on the end of the bolt, and means for engaging the washer to the bolt to prevent its rotation on the end thereof, in combination with a coöperating part of a diameter corresponding to that of the bolt and similarly screw-threaded, said part being provided with a cam face formed to coöperate with that of the washer, and means for engaging a tool with said part to rotate the same.

4. A lock-bolt comprising a screw-threaded bolt, a washer provided with a cam face adapted to rest on the end of the bolt and means for preventing the rotation of the washer, in combination with a coöperating part of the same diameter as the bolt and 130

similarly screw-threaded, provided with a cam face formed to engage with and coöperate with the cam of the washer, and means for temporarily engaging the washer and 5 said coöperating part to prevent the rotation of the latter when the nut is removed from the bolt.

5. A lock-bolt provided with a cam face on its free end, in combination with a follower extension of said bolt, provided with a corresponding cam face, and means for temporarily locking the two together while screwing a nut thereon or removing the same therefrom.

10 6. A lock bolt comprising a bolt provided with a cam face on its end, in combination with a follower provided with a coöperating cam face, one of said parts provided with a

guiding projection, and the other with an aperture arranged to loosely receive the 20 same.

7. A lock bolt comprising a bolt provided with a cam face on its end, in combination with a follower provided with a coöperating cam face, one of said parts provided 25 with a guiding projection, and the other with an aperture arranged to loosely receive the same, and means for temporarily locking the parts together as desired.

In testimony whereof, I have hereunto 30 signed my name in the presence of two subscribing witnesses.

EMIL C. ANDERSON.
